UNITED STATES PATENT OFFICE.

FRANK T. LYNCH, OF BALTIMORE, MARYLAND.

DUMPING-WAGON.

SPECIFICATION forming part of Letters Patent No. 601,476, dated March 29, 1898.

Application filed March 9, 1897. Serial No. 626,587. (No model.)

To all whom it may concern:

Be it known that I, FRANK T. LYNCH, of the city of Baltimore and State of Maryland, have invented certain Improvements in Dumping-Wagons, of which the following is a specification.

In the description of the said invention which follows reference is made to the accompanying drawings, forming a part hereof, and in which—

Figure 1 is an exterior side view of the improved dumping-wagon, with the body thereof in a horizontal position. Fig. 2 is a top view of Fig. 1. Fig. 3 is an exterior side view of the wagon as it appears when the body is tilted to dump the contents.

Referring now to the drawings, A is the frame, consisting of the two side pieces *a*, the end piece *b*, and the intermediate cross-pieces *c*.

The running-gear is attached in any suitable manner to the under side of the frame A.

B is the wagon-body, in two sections *d* and *e*, hinged, respectively, at *f* and *g* to the upper side of the frame A. The adjoining ends of the sections *d* and *e* are beveled, or, in other words, they are not at a right angle with the bottom, and they come closely together, so that when the body is in a horizontal position, as shown in Fig. 1, there exists no space between them. The abutting ends of the two sections of the body are bound exteriorly with iron straps *h* and *i* to strengthen them, and the inner surface of the section *e* has a similar strap *j*, which projects beyond the end of the section, against which the other section *d* comes in contact when the two sections are brought into alinement. By this arrangement a close joint is produced and leakage from the

body is prevented when the contents consist of finely-divided material, such as earth or sand. The rear end of the section *e* of the body is also provided with a strengthening-strap *k*, the upper ends of which are extended above the body to suspend the hinged tail-board C.

On each side of the front section *d* is a dumping-bar D, which extends beyond the end piece *b* of the frame A to be used as a handle in tilting the said section. These bars are held down when the body is not to be tilted or until the contents of the wagon are to be

dumped by means of a bar E and staples *m* on the frame.

In order that the rear section *e* of the body may be tilted simultaneously with the front section *d*, I attach the upper edge of the rear section to the dumping-bar D by a link F.

By connecting the links F to the dumping-bars D instead of directly to the sides of the front section of the body, as heretofore practiced, the said sides are not subjected to strains at points least adapted to withstand them, and a much stronger body is thereby produced. Further, by connecting the links F to the dumping-bars D at a point beyond the front end of the body a greater movement is imparted to the rear section of the body and the angle of inclination of the said section is brought nearer to that of the front one, as will be understood by referring to Fig. 3 of the drawings.

To automatically open the tail-board C as the body is tilted, I connect it to the dumping-bar D at each side by two bars G and H and unite them by an arm I, pivoted to the frame A, as shown in the drawings.

A chain K (shown in Fig. 3) serves to limit the tilting movement of the body.

By referring to Fig. 2 it will be seen that the body B of the wagon is tapered, as seen from the top, the narrower portion being at the front. The object in tapering the body is to facilitate the discharge of its contents, as will be readily understood.

The sections of the body being pivoted about centrally of their length, little effort is required to tilt them, and by dividing the body into sections, as shown, a greater angle of inclination can be attained than if the body were in one piece.

To tilt the body so as to dump the contents, the bar E is removed and the dumping-bar lifted.

I claim as my invention—

1. In a dumping-wagon, the body thereof in two sections pivoted independently to the frame, the front section having dumping-bars secured immovably thereto, and extend forward of and beyond the said section, combined with link-bars which pivotally connect the said dumping-bars at a point beyond the end of the body with the upper part of the rear

section, whereby as the said dumping-bars are elevated both sections of the wagon are tilted to near the same angle of inclination, substantially as specified.

5. 2. In a dumping-wagon, the body thereof in two sections pivoted independently to the frame, the front section having dumping-bars secured immovably thereto and extending forward of and beyond the said section, and 10 the rear section provided with a hinged tail-

board, combined with link-bars which connect the dumping-bars at a point beyond the body with the rear section of the body, and other link-bars which connect the dumping-bars at a point beyond the body with the tail-board, 15 substantially as specified.

FRANK T. LYNCH.
